CONTROL SYSTEM

William A. Ray, Los Angeles, Calif.

Application February 1, 1943, Serial No. 474,300

5 Claims. (Cl. 158—117.1)

My present invention relates to fluid-fuel burner control systems of the type which includes an electrically operated valve for controlling the supply of fuel and a thermoelectric generating device, adapted to be heated by combustion of the fuel employed in the system, for energizing the valve.

An object of the invention is to provide, in a control system of the character described, means for so controlling the heating of the thermoelectric generating device as to effect selective operation of the burner.

Another object is to provide, in a burner control system of the character described, a thermoelectric generating device of such capacity that it is capable of operatively energizing an electrically operated valve, of a size adapted to supply fuel to an ordinary space-heating "main" burner, without the requirement for supplemental power, such as that provided by the pressure of the supply fuel. An advantage of such "direct" electrical operation of the valve is the exclusion of the diaphragm customarily employed in a fluid-pressure operated valve, which diaphragm deteriorates rapidly if it is subjected to high temperatures adjacent a furnace. According to my invention, the thermoelectric generating device is operated only while the main-burner valve is open, so that no fuel is consumed by the auxiliary burner, provided for heating the thermoelectric generating device, while the heating system is out of operation.

A further object is the provision of an additional system for controlling the operation of the auxiliary burner for the thermoelectric generating device—which system includes an additional electrically operated valve, an additional thermoelectric generating device for energizing that valve, and an additional auxiliary burner (continuously burning) for heating the additional thermoelectric device; these parts being of such size and capacity that but a small amount of fuel is required for the operation of the auxiliary system.

It will be observed that the system of the present invention is capable of electrically controlling fuel supply to a relatively large capacity main burner, without the requirement for supplemental burner, and with minimum continuous consumption of fuel—while retaining the advantage, in-

herent in a thermoelectrically-energized system, of "safety shut-off" of the main burner (due to cessation of generation of electrical energy) in the event of accidental extinguishment of the auxiliary burners, when the same also serve as the means for igniting the main burner; and also the advantage due to the fact that the system is independent of the usual electrical service.

Other objects and advantages of the invention will be found in the description, the drawing, and in the claims; and for full understanding of the invention, reference may be had to the following detailed description and accompanying drawing, the single figure of which is a mainly diagrammatic view of a burner control system embodying my invention.

In the drawing, the numeral 11 generally indicates an electrically operated valve which controls passage of fluid fuel from a supply conduit 12 to a main burner 13. Connected to the inlet of the valve 11 is a pipe 14 which leads, through a branch pipe 15, to a second electrically operated valve 16. Connected to the outlet of valve 16 is a first auxiliary burner 17, positioned adjacent the main burner 13, which auxiliary burner serves to heat a first thermoelectric generating device, generally indicated at 18, comprising a plurality of thermocouples providing hot junctions 19 adapted to be heated by the flame 20 of auxiliary burner 17. While it may appear in the drawing that the device 18 extends partly over the main burner, it is to be understood that, in practice, it is so located that it is not in any way affected by the heat thereof. Connected, at the junction of pipes 14 and 15, to the fuel supply is a second auxiliary burner 21, the flame 22 of which is adapted to heat an additional thermoelectric generating device 23 which is similar to the device 18 but of smaller capacity. The thermoelectric device 18 is uninterruptedly connected by wires 24 to the valve 11, and the device 23 is connected by wires 25 to the second valve 16, this connection being through a limit control or thermostat 26 which comprises a bimetallic member 27 carrying a contact element 28 cooperable with a fixed contact 29.

The valve 11 comprises a casing 30 having a ported partition 31 providing an annular valve seat 32 upon which a disk-like closure member 33 normally rests. The closure member is of mag-

netic material and is attractable toward the closely-adjacent pole faces defined by the undersides of the enlarged free ends of the side arms of a U-shaped core 34, when the same is energized by passage of current through its coil winding 35. The electromagnet, constituted by core 34 and coil 35, is mounted within a housing 36 which covers an opening through the wall of the casing above the closure member; a thin diaphragm 37, of non-magnetic material such as brass, being interposed at its margin between the housing and the casing to shield the electromagnet from the fluid controlled by the valve, and also to serve as a non-magnetic separator between the pole faces and the armature-closure member 33. The valve 11 is of the type disclosed in my copending application, Serial No. 456,358, filed August 27, 1942, wherein it is taught that there is a considerable advantage in providing the core with enlarged pole-face-defining heads 38 when the flux density in the core is very low—such as that produced by an ordinary pilot-burner-heated thermoelectric generating device. The valve 16 is considerably smaller than valve 11 but is otherwise identical in construction, and its parts have therefore been assigned numerals which are the same as those of the corresponding parts in valve 11, except with a prime mark added.

As shown in the drawing, both of the valves are closed, so that neither the main burner 13 nor the large auxiliary burner 17 is in operation. The small auxiliary burner 21, however, is functioning since it is continuously supplied with fuel, and the small thermoelectric generating device 23 is therefore heated. The system, as illustrated, is under the automatic control of the thermostat 26, which, it may be assumed, is responsive to the heat produced by the main burner. When the bimetallic member 27, upon cooling, warps to contact-closing position, the energizing circuit of the small valve 16 is completed and its closure member 33' is therefore attracted to open position, fuel then passing to the large auxiliary burner 17 where it is ignited by the flame 22 of the small burner. The flame 20 issuing from burner 17 effects heating of the large thermoelectric generating device 18 so that, in a short space of time, energy is produced thereby in an amount sufficient to cause attraction to open position of the closure member 33 of the large valve 11; the fuel then passing to the main burner 13 being ignited by the flame of burner 17 or 21, these burners being so arranged that either of them can serve as a pilot burner for the main burner. When, in response to operation of the main burner, the thermostat subsequently opens the energizing circuit of the small valve 16, fuel supply to the large auxiliary burner 17 is stopped, and upon resultant cessation of generation of energy by the large thermoelectric device 18, due to the cooling thereof, the large valve 11 also closes, obstructing fuel supply to the main burner. In the event of extinguishment of the normally continuously-burning small auxiliary burner 21 during a period in which heating is discontinued, upon subsequent closing of the thermostat contacts no further result is produced inasmuch as no energy is then available for operating the small valve 16, and escape of additional unburnt fuel is thus prevented.

While I have herein shown and described a specific embodiment of my invention, I wish it to be understood that modifications may be made without departing from the spirit of the invention, and that I intend therefore to be limited only by the scope of the appended claims.

I claim as my invention:

- 5 1. In a burner control system: a main burner, an electrically operated valve for controlling supply of fuel to said main burner, a thermoelectric generating device for operatively energizing said valve and uninterruptedly connected thereto, a first auxiliary burner for heating said thermoelectric generating device, valve means operable between open and closed positions for controlling supply of fuel to said first auxiliary burner, and a continuously-burning second auxiliary burner for igniting the fuel at said first auxiliary burner, at least one of said auxiliary burners also serving to ignite the fuel at the main burner.
- 10 2. In a burner control system: a main burner, a first electrically operated valve for controlling supply of fuel to said main burner, a first thermoelectric generating device for operatively energizing said first valve, a first auxiliary burner for heating said first thermoelectric generating device, a second electrically operated valve for controlling supply of fuel to said first auxiliary burner, a second thermoelectric generating device for operatively energizing said second valve, a second auxiliary burner for heating said second thermoelectric generating device, and means for controlling the energization of said second valve, at least one of said auxiliary burners also serving to ignite the fuel at said main burner.
- 15 3. In a burner control system: a main burner, a first electrically operated valve for controlling supply of fuel to said main burner, a first thermoelectric generating device for operatively energizing said first valve, a first auxiliary burner for heating said first thermoelectric generating device, a second electrically operated valve for controlling supply of fuel to said first auxiliary burner, a second thermoelectric generating device for operatively energizing said second valve, a second auxiliary burner for heating said second thermoelectric generating device, and means for controlling the energization of said second valve, said first thermoelectric generating device being so constructed that it is capable of generating power considerably in excess of that generated by said second thermoelectric generating device.
- 20 4. In a burner control system: a main burner, a first electrically operated valve for controlling supply of fuel to said main burner, a first thermoelectric generating device for operatively energizing said first valve and uninterruptedly connected thereto, a first auxiliary burner for heating said first thermoelectric generating device, a second valve for controlling supply of fuel to said first auxiliary burner and electrically operable between open and closed positions, a second thermoelectric generating device for operatively energizing said second valve, a continuously-burning second auxiliary burner for heating said second thermoelectric generating device and having a fuel capacity which is small as compared with that of said first auxiliary burner, and means for controlling the energization of said second valve.
- 25 5. In a burner control system: a main burner, a first electrically operated valve for controlling supply of fuel to said main burner, a first thermoelectric generating device for operatively energizing said first valve and uninterruptedly connected thereto, a first auxiliary burner for heating said first thermoelectric generating device, a second valve for controlling supply of fuel to said first auxiliary burner and electrically operable

between open and closed positions, a second thermoelectric generating device for operatively energizing said second valve, a continuously-burning second auxiliary burner for heating said second thermoelectric generating device and having a fuel capacity which is small as compared with that of said first auxiliary burner, at least one

of said auxiliary burners also serving to ignite the fuel at said main burner, and thermostatic means responsive to the operation of said main burner for controlling the energization of said second valve.

WILLIAM A. RAY.
